UNITED STATES PATENT OFFICE.

THEODORE W. MUNFORD, OF PITTSBURGH, PENNSYLVANIA, ASSIGNOR TO MANTLE ENGINEERING COMPANY, A CORPORATION OF PENNSYLVANIA.

HEAT-EXCHANGE APPARATUS.

Application filed April 9, 1928. Serial No. 100,844.

This invention relates to heat exchange apparatus and more particularly to the type used in connection with a flue chamber or the like for the purpose of utilizing the heat 5 of combustion gases for the purpose of raising the temperature of a fluid such, for example, as air passed through the apparatus.

Although the most form efficient of heat exchanger is the straight counter flow type, 10 in which the direction of flow of the fluid passing through the apparatus to be heated is opposite to the direction of flow of the heating gases, this type has certain practical disadvantages which result from the fact 15 that that part of the apparatus which is exposed to the highest temperature of the heating gases is also the part conveying the hottest fluid to be heated with the result that the temperature of the material from 20 which the heat exchanger is constructed at that point may be so high as to materially reduce the effective life of the structure. In view of the fact that the counter flow type of heat exchanger insures the greatest 25 mean temperature difference between the fluid to be heated and the heating gases, this type of apparatus takes the greatest advantage of the convected heat but fails, on the other hand to efficiently utilize the radiant 30 heat available from sources outside of the heating gases such, for example, as the brick settings of the associated flue chamber or the like, and this is due to the fact that such heat is most intense at the point where the heating 35 fluid enters the apparatus which, in a counter flow type, is also the point where the fluid to be heated is hottest so that the heat transfer at this point is relatively low, due to the fact that, as stated in Stefan- 40 Boltzmann's law, the rate of heat transfer by radiation from a hotter to a cooler body is proportional to the difference in the fourth powers of their absolute temperatures.

An object of this invention is to provide 45 a heat exchange apparatus of such construction and arrangement that the flow of fluid to be heated through that part of the apparatus subjected to the highest temperature can be given a predetermined characteristic such, for example, as quantity flow,

regardless of the total flow through the apparatus.

A further object is to provide a device of the type set forth of such construction and arrangement as to obtain the utmost effect 55 of the radiant heat of the associated structure and at the same time maintain the greatest mean temperature difference between the temperature of the heating gases and that of the fluid to be heated so as to 60 obtain the most efficient transfer of heat.

These and other objects which will be obvious to those skilled in this particular art are attained by means of this invention, one form of which is illustrated in the accompanying drawing, which shows a sectional view through part of a heat exchange apparatus constructed in accordance with one embodiment of this invention.

The particular embodiment of this invention which has been chosen for the purposes of illustration includes a fluid transmitting chamber or section provided with an arrangement of conduits or passages through which the fluid to be heated, such as air, is 70 passed. Two passages are provided adjacent that end of the structure which is subjected to the highest temperature, the bottom 75 in the illustrated form, and these passages are associated in parallel relation for the 80 transmission of separate streams of fluid directed thereto from separate inlets. Each passage leads to the same duct or manifold where the two streams are united and through which they flow to a third passageway 85 positioned in series relationship with the preceding passageways and from which the fluid is carried to the outlet of the apparatus. As illustrated, the two passageways in parallel relation are so formed as to 90 direct the respective streams of air passing therethrough in a cross parallel direction with relation to the direction of the heating gases while the third passageway in series with the two preceding passageways is so 95 formed as to direct the combined streams in a cross counter flow with relation to the heating gases. The direction of flow of the heating gases between the assembled sections is indicated by the arrow "A" on

the drawing. Although the drawing illustrates a single fluid transmitting section it will, of course, be apparent that any number of these sections can be assembled with proper manifolding to provide a heat exchange apparatus of any desired size, as more fully described in copending applications, Serial Nos. 41,135 and 100,862 filed July 2, 1925, and April 9, 1926, respectively.

10 As illustrated, each section is provided with a fluid inlet 5 associated with an inlet manifold 6 leading to an entrance 7 of a passageway or conduit 8 formed adjacent that end of the section which is subjected to 15 the highest temperature both from the flue gases and the radiant heat of the associated flue chamber. The air flows through the passage 8 in a circuitous route formed by suitable positioned baffles 9 and also in a 20 generally upward direction parallel to the flow of the heating gases and thence outwardly through an opening 10 into a manifold 11. A baffle 12 is positioned in the manifold 11 opposite the opening 10 for the 25 purpose of directing the stream of air issuing therefrom into the extreme end of the manifold 11 so as to prevent the formation of a dead air pocket in the manifold between the end thereof of the outlet opening 30 10 which would result in such a high temperature at that point as to cause rapid deterioration of the material forming the apparatus.

35 A second inlet 13 admits a separate stream of air to a second inlet manifold 14 leading to the entrance 15 of a second passageway 16 associated with the first passageway 8 in parallel relation and through which the second stream of air flows in a circuitous 40 route formed by baffles 17 into an outlet 18 leading to the manifold 11.

The two streams of air issuing from the 45 passages or conduits in parallel with each other combine in the manifold 11 to form a single stream of air which passes through an opening 19 adjacent the opposite end of the apparatus into a passageway or conduit 20 through which it flows in a circuitous route formed by baffles 21 in a direction 50 counter to the flow of the heating gases. The stream emerges from the counter flow passage 20 through an opening 22 to a manifold 23 through an outlet duct 24 at the top of the device to an outlet 25. A valve 55 26 is associated with each inlet so as to provide a means for separately controlling the flow of the parallel streams of air admitted to the apparatus and an automatic control for the separate streams of air can be provided as described in the copending applications, above referred to, to as to obtain 60 flexibility of operation.

It will be apparent that either or both sets of baffles 9 and 17 in the two lower 65 passages or conduits 8 and 16, respectively,

can be omitted so that the respective streams of air will flow across the hot end of the apparatus in a straight cross current direction.

By directing two streams of relatively 70 cold air immediately into the hottest part of the apparatus the utmost advantage is taken of the radiant heat of the flue gases and the associated flue chamber construction. The introduction of relatively cold fluid at 75 this point maintains the material from which the apparatus is constructed at a temperature within safe limits and the most efficient heat transfer is effected. At the same time the provision of a counter flow chamber in 80 series with two cross flow chambers insures the greatest mean temperature difference between the heating gases and fluid passing through the apparatus so that the utmost effect is obtained from the convected heat of 85 the flue gases.

Although I have described a specific form 90 of heat exchange apparatus it will be apparent that various changes, additions, omissions and substitutions can be made therein without departing from the spirit of the invention or the scope of the appended claims.

What I claim as new and desire to secure by Letters Patent is:

95 1. A heat exchange apparatus having in combination a plurality of conduits for the passage of fluid to be heated assembled in parallel relation for the passage of separate streams of fluid through that part of the 100 apparatus subjected to the highest temperature and a counter flow passage in series with said conduits for directing the fluid issuing from each of said conduits in a direction counter to the flow of the heating 105 gases.

110 2. A heat exchange apparatus having in combination, a conduit for directing a stream of air through that part of the apparatus subjected to the highest temperature, an inlet for admitting relatively cold air thereto, a second conduit adjacent said first conduit, an inlet for admitting a separate stream of relatively cold air to said second conduit, an air duct, an outlet from each conduit thereto and a third conduit for directing the air from said duct through the apparatus in a direction counter to the direction of flow of the heating gases.

115 3. A heat exchange apparatus having in 120 combination passages for conveying separate streams of fluid to be heated through the hottest part of said apparatus, means for uniting said streams and a passage for directing said united streams in a direction counter to the direction of flow of the heating gases with which said apparatus is associated.

125 4. A heat exchange apparatus having in combination a plurality of passages for con-

veying separate streams of air through that part of the apparatus subjected to the highest temperature, a duct to which said passages lead and wherein said streams are 5 united, an outlet and a passage between said duct and said outlet for directing the united streams through a part of said apparatus in

a direction counter to the direction of flow of the heating gases.

In testimony whereof, I have hereunto 10 subscribed my name this 2nd day of April 1926.

'THEODORE W. MUNFORD.
